UNITED STATES PATENT OFFICE.

HENRY WILLIAMS, OF DETROIT, MICHIGAN, ASSIGNOR TO WILLIAMS BROS. & CHARBONNEAU, OF SAME PLACE.

DESIGN FOR A BOTTLE.

SPECIFICATION forming part of Design No. 23,834, dated December 4, 1894.

Application filed September 18, 1894. Serial No. 523,416. Term of patent 7 years.

To all whom it may concern:

Be it known that I, HENRY WILLIAMS, a citizen of the United States, residing at Detroit, in the county of Wayne and State of Michigan, have invented and produced a certain new and original Design for Bottles, of which the following is a specification, reference being had therein to the accompanying drawings.

The invention relates to a new and original design for bottles and is illustrated in the accompanying drawings, wherein—

Figure 1 is an elevation of a bottle embodying the design, and Fig. 2 is a cross section thereof.

The design consists essentially in a cylindrical body portion having a tapering neck B, the ring or flange C at the upper edge of the neck. The surface of the cylindrical portion is divided into plain vertical spaces E, G,

separated by the fanciful panel spaces having thereon the diagonal grooves H' arranged one above the other, the grooves of one panel inclining in a direction opposite that of the other panel, and each panel is bordered by the vertical groove I on opposite sides.

The essential features of the design are the peculiar shape of the bottle, the special decorations thereon, and the arrangement of the decorative features all as shown.

What I claim is—

The design for a bottle, substantially as shown and described.

In testimony whereof I affix my signature in presence of two witnesses.

HENRY WILLIAMS.
